UNITED STATES PATENT OFFICE.

FRANK B. MARTIN, OF BATTLE CREEK, MICHIGAN, ASSIGNOR TO POSTUM CEREAL CO., LIMITED, OF BATTLE CREEK, MICHIGAN, A PARTNERSHIP ASSOCIATION LIMITED, OF MICHIGAN.

FLAP-CLOSING DEVICE FOR CARTONS.

1,119,091.

Specification of Letters Patent.

Patented Dec. 1, 1914.

Application filed June 12, 1912. Serial No. 703,246.

To all whom it may concern:

Be it known that I, FRANK B. MARTIN, of Battle Creek, Michigan, have invented a new and useful Improvement in Flap-
5 Closing Devices for Cartons, which invention is fully set forth in the following specification.

The present invention relates to carton-closing devices, and the particular object
10 of the present invention is to provide an improved structure for folding the end flaps of cartons.

By the use of the improved device which embodies an intermittently rotating folding mechanism, the rear end flap of each carton is folded in under the front end flap, with the result that all danger of the rear end flap being caught by the mechanism for gluing and sealing the cartons is ob-
15 viated.

The invention will be better understood by reference to the accompanying drawing, wherein—

Figure 1 is a transverse section, partly in elevation, of a carton conveying machine provided with the improved device, looking in the direction of feed of the cartons; Fig. 2 is a side elevation of the rear end flap folding mechanism and its actuating parts; and Fig. 3 is a perspective view, showing the device for folding the front end flap over the rear end flap.

Referring to the drawings, 4, 4, are feed belts or conveyers which carry the filled cartons, and 5—5 are tracks or ways onto which the cartons are shifted laterally by any suitable mechanism, not shown. Associated with these tracks or ways are followers 6—6, which are carried by any suitable means, as endless chain 7. These followers 6 engage the cartons and progress them past the improved end flap sealing mechanism, to be described, and then to any suitable gluing and sealing devices.

The rear end flap folding mechanism comprises a shaft 8, here shown as mounted in brackets 9 suitably secured to the frame of the machine, which shaft is intermittently driven by suitable mechanism. As herein illustrated, a gear 10 is mounted on

one end of this shaft, and a driving chain 11 passes around this gear and a gear 12 which is fixedly mounted on a shaft 13. Said shaft 13 also has fixed thereon a ratchet 14, and loosely mounted thereon is an arm 55 or lever 15 on which is pivoted a pawl 16 which, at the proper time, engages the ratchet 14 to impart movement to shafts 8 and 13. The lever 15 is operated by any suitable mechanism, and as herein shown, 60 a rod 17 is connected at one end to the upper end of said lever, and the other end of said rod is eccentrically connected to a rotary member 18 which is driven by any suitable mechanism.

The front end flap folding device is preferably a stationary plate 18', which is suitably secured to the frame of the machine, and the means that engage the rear end flaps of the cartons to fold the same are 70 preferably a plurality of arms 19, suitably secured to shaft 8 and equidistantly spaced, each of said arms being provided with a finger 20 projecting at right angles therefrom.

The operation of the device is as follows:—The mechanism is so timed that as each carton approaches the end flap folding devices, one of the arms 19 is rotated into engagement with the rear end flap and folds 80 the same, this movement of the arm being caused by the engagement of pawl 16 with one of the teeth of ratchet 14. When said ratchet has been rotated by the pawl to the limit of the forward movement of the latter, 85 the positive driving of shaft 8 ceases, and it momentarily becomes stationary, as does the arm that is in engagement with the rear end flap of the carton, said arm at this time holding down said flap. The 90 movement of the carton continues during this momentary stopping of the arm which is in engagement with the flap. By reason of the frictional engagement between the arm and the flaps, the continued movement 95 of the carton carries with it the engaging arm, thus insuring that the front end flap shall be folded over the rear end flap by the folding plate 18'. Thereafter, the pawl 16 is again in position to rotate shafts 13 100

and 8 by engaging the next tooth on ratchet 14, and the foregoing operation is repeated, the succeeding rotary arm 19 engaging the rear end flap on the next carton.

5. What is claimed is:—

1. In combination, a continuously-moving carton conveyer, a front flap folding device, a rear flap folding device, means for moving said latter device into engagement with the rear flap and holding said device substantially stationary while the carton acted upon is moved by said conveyer relatively to said device.

10. 2. In combination, a continuously-moving carton conveyer, a front flap folding device, a rear flap folding device, means for rotating said latter device into engagement with the rear flap and holding said device substantially stationary and in engagement with said rear flap while the carton acted upon is moved by said conveyer relatively to said device.

15. 3. In combination, a front flap-folding device, a rear flap-folding device, a continuously-moving carton conveyer carrying cartons past said folding devices, a continuously-moving element, and connections between said element and said rear flap-folding device whereby the latter is operated intermittently and is stationary while acting in coöperation with the conveyer upon the carton.

20. 4. In combination, a front flap-folding device, a rear flap-folding device, a continuously-moving carton conveyer carrying cartons past said folding devices, a continuously-rotating element, and connections between said element and said rear flap-folding device whereby the latter is operated intermittently and is stationary while acting in coöperation with the conveyer upon the carton.

25. 5. In combination, a front flap folding device, a rear flap folding device, a continuously rotating driving element, an element intermittently rotating in only one direction, connections between said rear flap-folding device and said intermittently rotating element, and driving connections between said continuously rotating element and said intermittently rotating element.

30. 6. In combination, a front flap folding device, a rear flap folding device, a continuously moving element, an element intermittently moving in only one direction, connections between said rear flap-folding device and said intermittently moving element, and driving connections between said continuously moving element and said intermittently moving element.

35. 7. In combination, a front flap folding device, a rear flap folding device rotating only in one direction, a continuously rotating element, a shaft, a ratchet fixedly mount-

ed thereon, a lever loosely mounted on said shaft, a pawl carried by said lever, connections between said rear flap folding device and said shaft, and connections between said lever and element.

40. 8. In combination, a front flap folding device, a rear flap folding device rotating only in one direction, a continuously moving element, a shaft, a ratchet fixedly mounted thereon, a lever loosely mounted on said shaft, a pawl carried by said lever, connections between said rear flap folding device and said shaft, and connections between said lever and element.

45. 9. In combination, a front flap folding device, a rear flap folding device rotating only in one direction, a shaft, connections between said rear flap folding device and said shaft, an element fixedly mounted on said shaft, a second element loosely mounted on said shaft, and means moving said second element into engagement with the first element to rotate said shaft.

50. 10. In combination, a carton conveyer, a front flap folding device, a rear flap folding device rotating only in one direction, a shaft, connections between said shaft and the rear flap folding device, a ratchet fixedly mounted on said shaft, a lever loosely mounted on said shaft, a pawl carried by said lever and engaging said ratchet, and means for rocking said lever to rotate said shaft.

55. 11. In combination, a front flap-folding device, a rear flap-folding device, a continuously-moving carton conveyer carrying cartons past said folding devices, and means intermittently operating said rear flap-folding device which remains stationary while acting in coöperation with the conveyer upon the carton.

60. 12. In combination, a front flap-folding device, a rear flap-folding device provided with a plurality of arms, a continuously-moving carton conveyer carrying cartons past said folding devices, and means intermittently moving said arms into engagement with the rear flaps of the cartons on said conveyer, said arms remaining stationary while acting in coöperation with the conveyer upon the carton.

65. 13. In combination, a front flap-folding device, a rear flap-folding device provided with a plurality of arms, a continuously-moving carton conveyer carrying cartons past said folding devices, and means intermittently rotating said arms into engagement with the rear flaps of the cartons on said conveyer, said arms remaining stationary while acting in coöperation with the conveyer upon the carton.

70. 14. In a device of the character described, the combination of a continuously-moving conveyer adapted to carry a stream of car-

tons, a front flap-folding device, a rear flap-folding device, and means intermittently engaging said rear flap-folding device with the rear flaps of the cartons, said rear flap-folding device remaining stationary while acting in coöperation with the conveyer upon the cartons.

In testimony whereof I have signed this specification in the presence of two subscribing witnesses.

FRANK B. MARTIN.
